DEVICE FOR CLEANING AND REMOVING
DUST FROM MOPS AND OTHER SIMI-
LAR KINDS OF BROOMSMarta Schultze, née Liehr, Berlin Friedenau,
GermanyApplication August 17, 1936, Serial No. 96,460
In Germany October 20, 1935

2 Claims. (Cl. 15—104)

The object of the invention is a device for cleaning and removing dust and dirt from mops and other similar kinds of brooms, by means of which the dust and dirt can be removed immediately after the use thereof.

The invention has for its object to produce a device for cleaning and removing dust from mops of simple construction, embodying a minimum number of working parts, and attaining the highest degree of reliability in practical use.

With this invention it is possible to carry out with one hand all preparatory movements for shaking out and cleaning the mop, so that the handle of the mop, whilst being held in the free hand, need not be laid down, a circumstance which is of special importance in so far as in order to clean one single room only it is necessary to shake out the mop several times.

The invention is shown in an example in the annexed drawing, in which: Fig. 1 is the container of the device in section without the mop, and Fig. 2 is a section through the container of the device with the mop inserted in it. A preferred construction is shown in which 1 is the container with a small quantity of water, 2 is a spiral spring arranged upon the bottom of the container and furnished at its upper end with a straight part 2a with the plate 3, 4 is a guiding bar attached to the side walls of the container, 5 is the lid of the container diagonally divided and provided with a hole for the handle of the mop, 6 is the mop and 7 the handle of the mop.

The device of the invention acts in the following manner:—

After opening up the divided halves of the lid and pouring a small quantity of water into the container 1, the mop 6 with its handle 7 in an upward direction is placed upon the plate 3. The device is then closed down by means of both the halves of the lid in such a manner that only the handle 7 is to be seen. The handle 7 is then pressed downwards vertically by the hand so that the spring 2 is depressed. The handle is then drawn upwards, whereby the action of the spring

counter-acts the weight of the mop and the arm of the operator, that is to say, the action of the spring carries out the work of the hand, facilitating same. By means of the rapid up-and-down movement of the handle 7 the mop is thoroughly cleaned, the particles of dust and dirt thereupon falling into the water at the bottom of the container and remaining there. After opening the top parts of the container the mop is taken out and the container is rapidly closed down.

The spring may be made of any suitable wire, for example of circular, square or rectangular section.

The lid is preferably constructed of two separate parts each part possessing a semi-circular hole. One of the halves of the lid is fixed to the container, whilst the other half is attached to the wall of the container by means of a hinge and a spring, so that this part opens upwards and closes automatically, thus shortening the period in which dust particles are free to leave the container.

What I claim is:—

1. Device for a dust free cleaning of mops or other similar kinds of brooms, consisting of a container with a lid, an opening in the lid for the handle of the mop, and a spiral spring for supporting the mop, this spiral spring resting upon the bottom of the container and being provided with a straight part co-axial with the axis of the spring and guided by means of a guiding part in the container.

2. Device for a dust free cleaning of mops or other similar kinds of brooms, consisting of a container with a lid, an opening in the lid for the handle of the mop, and a spiral spring for supporting the mop, this spiral spring, resting upon the bottom of the container, being provided with a straight part guided by means of a guiding part in the container, and being provided with a plate for supporting the mop.
